(57) **CLAIM**

The ornamental design for an electric foldable scooter, as shown and described.

DESCRIPTION

FIG. 1 is a perspective view of an electric foldable scooter showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged partial view of the handlebars area taken from the top of FIG. 1;

FIG. 10 is an enlarged partial view of the front wheel area taken from the bottom left of FIG. 1;

FIG. 11 is an enlarged partial view of the rear wheel area taken from the bottom right of FIG. 1;

FIG. 12 is an enlarged partial view of the side area taken from the bottom middle of FIG. 1;

FIG. 13 is an enlarged partial view of the handlebars area taken from the top of FIG. 2;

FIG. 14 is an enlarged partial view of the front wheel area taken from the bottom right of FIG. 2;

FIG. 15 is an enlarged partial view of the rear wheel area taken from the bottom left of FIG. 2; and,

FIG. 16 is an enlarged partial view of the bottom rear wheel area taken from the bottom of FIG. 8.

The dash-dash broken lines in the drawings depict portions of the electric foldable scooter that form no part of the claimed design. The dot-dash broken lines represent boundaries of the enlarged portions and form no part of the claimed design.
